[57] CLAIM

The ornamental design for a necklace, substantially as shown and described.

DESCRIPTION

FIG. 1 is a front elevational view of a necklace showing my new design;

FIG. 2 is a top edge view thereof;

FIG. 3 is a rear elevational view thereof;

FIG. 4 is a bottom edge view thereof; and

FIG. 5 is a side elevational view thereof looking from the left with respect to FIG. 1, the opposite side being the mirror image thereof.
